CONTAINER FOR FLOWABLE MATERIALS OR THE LIKE

Richard E. Roe, Clare, Mich., assignor to Koehring Company

Filed Mar. 16, 1973, Ser. No. 341,967

Term of patent 14 years

Int. Cl. D9—01

U.S. Cl. D9—125

FIG.1

FIG.4

FIG. 1 is an elevational view, partially in section, of a container for flowable materials or the like showing my new design;

FIG. 2 is a top plan view;

FIG. 3 is a bottom plan view; and

FIG. 4 is a fragmentary sectional view showing the bottom portion thereof.

I claim:

The ornamental design for a container for flowable materials or the like, as shown.
